UNITED STATES PATENT OFFICE.

JOHN J. DEVINE, OF MIDDLETOWN, CONNECTICUT.

ILLUMINATED FOUNTAIN PEN.

Application filed March 20, 1924. Serial No. 700,595.

To all whom it may concern:

Be it known that I, JOHN J. DEVINE, a citizen of the United States, residing at Middletown, in the county of Middlesex and State 5 of Connecticut, have invented certain new and useful Improvements in Illuminated Fountain Pens, of which the following is a specification.

This invention relates to a fountain pen, of 10 the illuminable type, and has for its object to provide a pen of such class, in a manner as hereinafter set forth, with automatically shiftable means to provide for the illumination of a writing surface at and surrounding 15 the writing point when using the pen.

A further object of the invention, is to provide a pen of such class, in a manner herein-after set forth, with a lamp for illuminating the writing surface and to so position the 20 lamp within the pen body to provide for an increase in size of the ink reservoir, whereby the ink carrying capacity of the reservoir will be materially greater than the capacity of the reservoirs used in fountain pens of the 25 same class.

A further object of the invention is to provide a pen of the class referred to, in a manner as hereinafter set forth, with new and novel means whereby the lamp, the socket 30 therefor, and the holder for the lamp and socket can be quickly and conveniently inserted and removed from the pen body when occasion requires, and further to prevent said holder from accidentally sliding out of position from within the pen body.

A further object of the invention is to provide a pen of the class referred to, in a manner as hereinafter set forth, with means for utilizing a flat battery for the lamp, whereby 40 a pen body can be set up of reduced length, with respect to a pen of the class referred to employing a battery of tubular shape.

A further object of the invention is to provide a pen of the class referred to, in a manner as hereinafter set forth, with a removable 45 soft rubber ink reservoir capable of being self filled, and further capable of being

quickly positioned within and removed from the pen body and by such provision a reservoir of simple construction is employed resulting in expeditious manufacture of the reservoir and the quick setting up of the fountain pen.

A further object of the invention is to provide, in a manner as hereinafter referred to, 50 a pen of such class, with means whereby the ink does not come in contact with any metal part of the pen body when the pen is employed or not in use.

Further objects of the invention are to provide, in a manner as hereinafter set forth, a 55 fountain pen of the illuminable type, which is comparatively simple in its construction and arrangement, strong, durable, compact, thoroughly efficient and convenient in its use, 60 readily assembled, and comparatively inexpensive to manufacture.

With the foregoing and other objects in view, the invention consists of the novel construction, combination and arrangement of 70 parts as hereinafter more specifically described, and illustrated in the accompanying drawings, wherein is shown an embodiment of the invention, but it is to be understood that changes, variations and modifications 75 can be resorted to which fall within the scope of the claims hereunto appended.

In the drawings, wherein like reference characters denote corresponding parts throughout the several views:—

Figure 1 is a side elevation, broken away, 80 of a fountain pen, in accordance with this invention, with the protecting cap for the pen point in position.

Figure 2 is a longitudinal sectional view 85 of the fountain pen, in accordance with this invention, showing the protecting cap for the pen point removed from protecting position with respect to the pen point and attached to the pen body rearwardly of the pen point.

Figure 3 is a side elevation of a fountain pen, in accordance with this invention, and illustrating the protecting cap for the pen

point removed from protecting position and attached to the pen body rearwardly of the pen point.

Figure 4 is a section on line 4—4 of Figure 2.

Figure 5 is a section on line 5—5 of Figure 2.

Figure 6 is a section on line 6—6 of Figure 2.

Figure 7 is a section on line 7—7 of Figure 2.

Figure 8 is a longitudinal view of the inner shell.

Figure 9 is a top plan view of the inner shell.

Figure 10 is a bottom plan view of the inner shell.

Figure 11 is a section on line 11—11 of Figure 8.

Figure 12 is a perspective view of the holder for the lamp socket and the contact element associated with the lamp socket.

Referring to the drawings in detail, a fountain pen, in accordance with this invention, comprises a pen body formed of a hollow polygonal shaped section 1 and a hollow cylindrical section 2 formed at one end with a polygonal shaped extension 3, which is vertically disposed, and formed with a flange 4, inset with respect to the edges of the extension 3, whereby a shoulder 5 is formed. The flange 4 has a series of openings 6 for the reception of lugs 7 carried by the section 1 whereby the latter and the section 2 are detachably connected together.

The section 1 provides a battery chamber 7' which is of greater length than the length of the battery 8 encased by the section 1. The battery 8 is of the same shape as the shape of the section 1 and when the pen is in position to be used the battery 8 slides towards that end of the section 1 which is connected to the flange 4.

When the section 1 is mounted in position, with respect to the section 2, the section 1 is seated upon the flange 4 and abuts against the shoulder 5 and the lugs 7 extend into the openings 6 whereby the sections are detachably connected together. The section 1 is narrow so that the battery 8 mounted therein will be flat and by setting up the section 1 to receive a flat battery the length thereof can be materially reduced, which would not be the case if a tubular battery was employed.

The section 2 is of substantial length and diameter and projects from the lower part of the extension 3 and the diameter of the section 2 is substantially equal to the width of the extension 3. The cylindrical portion of the section 2 is integral with the extension and said cylindrical portion provides a sleeve which has the part thereof in proximity to the extension 3 threaded as at 9.

The extension 3 is formed with an opening which registers with the cylindrical part of the section 2 and the said opening is indicated at 10, and above the opening 10, in proximity to the upper end of the extension 3, the latter is provided with an opening 11 and an upwardly inclined interiorly threaded sleeve 12 which registers with the opening 11 and the function of the sleeve 12 will be presently referred to. 75

Extending across the opening 11 and arranged against the inner face of the extension 3, is a contact member 13, secured in position by the holdfast devices 14. The opening 10 in the extension 3 establishes 80 communication between the cylindrical part of the section 2 and the battery chamber 7'.

The battery 8 is provided with a terminal 15 which cooperates with the contact 13 and said battery 8 is furthermore provided with 85 a substantially elongated terminal 16 extending to the opening 10 for the purpose to be presently referred to.

Threadably connected to and arranged within the section 2 of the pen body is an 90 inner shell of substantial length and diameter and which is formed of an intermediate portion 17, an inner end portion 18, and a forward end portion 19. The end portion 18 is threaded for engagement with 95 the threaded inner portion 9 of the section 2 of the pen body whereby the inner shell is detachably connected to the section 2. The end portion 19 is of tapering contour and has the sides thereof cut inwardly in a 100 semi-circular manner as at 20.

The intermediate portion 17 between its center and the end portion 19 is formed with a circular opening 21 and at a point between its center and the end portion 18 105 is slotted as at 22, and the material freed by the slit is bent to extend inwardly of the portion 17 to form a semi-circular stop lug 23. The intermediate portion 17, directly below the opening 21 is formed with 110 a rectangular opening 24 which communicates at its rear with a longitudinally extending rectangular slot 25. The intermediate portion 17, has its bottom slotted as at 26, 27, and the material freed by the 115 slits 26 and 27 is bent inwardly to form a pair of oppositely disposed longitudinally extending supporting flanges 28, 29.

Disposed axially of the inner shell, as well as projecting forwardly therefrom, and of 120 a length to terminate in proximity to the forward end of the intermediate portion 17, of said inner shell, is a metallic sleeve 30, having formed integral therewith a series of radially disposed arms 31 which are connected to the inner faces of the portions 17 and 19 of the inner shell. Extending through the sleeve 30, as well as being secured therewith by the rivet 32, is a hard 125 rubber tube 33 having projecting from its 130

outer end the pen point 34 and feeder 35. The rear end of the tube 33 has projecting therefrom a curved extension 36, which extends into and is secured with a hollow soft 5 rubber body 37, which provides the ink reservoir 38 and said extension 36 communicates with the reservoir 38 for conducting the ink to the feeder 35, for the purpose of supplying the ink to the pen point 34. The 10 soft rubber receptacle 37 is arranged forwardly of the lug 23 and is also mounted upon a lamp socket holder to be presently referred to. As shown in Figure 6 the soft rubber receptacle 37 snugly engages the inner face of the inner shell. The curved extension 36 communicates with the upper portion of the receptacle 37 as shown in Figures 2 and 6.

The opening 21, in the intermediate portion 17, of the inner shell, provides means when the inner shell is removed, whereby the receptacle 37 can be compressed for the purpose of self filling, in connection with the opening 24. The filling of the reservoir 38 can be had without detaching it from the tube 33 or detaching the latter from the sleeve 30.

The receptacle 37 is formed with a neck 39 and to this neck is secured the curved extension 36, and with the neck arranged at the upper portion of the receptacle 37. Arranged below the neck 39 is a lamp 40 provided with a plug 41. Associated with the plug 41 for the purpose of positioning the lamp within the inner shell is a holder formed of a hollow body portion 42 providing a socket of substantial length having its wall threaded as at 43 and extending into the body portion 42 and engaging with the threads 43 is the plug 41. In longitudinal section the body portion 42 gradually decreases in height rearwardly and the socket formed thereby therein also extends at an inclination whereby the plug 41 will 45 be disposed at an upward inclination with respect to the bottom of the section 2 and in a manner as shown in Figure 2.

Each side of the body portion 42 is formed near its bottom with a lengthwise extending shoulder 44, and said shoulders 44 when the body portion 42 is in position, abut against the lower face of the flanges 28 whereby the said flanges in connection with the bottom of the section 2 will slidably secure the body portion 42 in position. The shoulders 44 terminate at a point removed from the forward and the rear end of the body portion 42. The plug 41 is of greater length than the length of the body portion 42 so that the plug will project rearwardly therefrom as shown in Figure 2.

Formed integral with the rear end of the body portion 42 is a vertically extending arm 45 having projecting rearwardly therefrom, at a point below the top thereof, an

enlargement 46 formed with a vertically disposed opening 47, and arranged within the opening 47 is a sleeve 48 of insulation which has an extension 49 terminating at the upper end of the arm 45. 70

Supported by the arm 45 and insulated therefrom through the medium of the insulation member 48 is an inverted hook shaped contact member 49 which is in electrical contact with the plug 41 and terminal 16. The 75 member 49 extends up through the insulation member 48, arranged in the enlargement 46, and is bent as at 50 to project rearwardly therefrom and in the path of the terminal 16. 80

When the battery 8 shifts towards the section 2 of the pen body, the terminal 15 engages the contact 13 and as the terminal 16 abuts the projecting portion of the member 49 the lamp circuit is closed. The plug 85 holder has its arm 45 abutting against the lug 23. When the lamp circuit is closed the circuit is set up by terminal 16, member 49, plug 41, plug holder, lug 23, inner shell, section 2 of the pen body, contact 13 and 90 terminal 15.

The reference character 51 indicates a cylindrical protecting cap for the pen point 34 and which is detachably mounted on the section 2 of the pen body and has its onward 95 movement arrested by a bead 52 formed on the periphery of the section 2 in proximity to its free end thereof. The cap 51 has its closed end formed with an exteriorly arranged peripherally threaded lug 53, which 100 engages with the interiorly threaded sleeve 12, for detachably connecting the cap to the extension 3 when occasion requires, and further is of a length to force the contact 13 rearwardly to a point in proximity to the 105 terminal 15.

By setting up the battery 8 to shift, in a manner as stated, the lamp circuit will be automatically closed when the pen is in position for writing or when the pen is tilted in a direction so that the battery 8 can shift to have the terminal 15 thereof engage the contact 13. The battery 8 automatically shifts to open the circuit when the pen is positioned whereby the pen point 34 will 110 extend upwardly, or the circuit is opened by the contact 13 returning to normal position when the lug 53 is out of engagement therewith.

The section 1 of the pen body can be set 115 up of any suitable material but the section 2 can have the cylindrical part thereof of non-conducting material, and the extension 3 of conducting material, in view of the fact that when the inner shell is mounted in position, it has contact with the extension 3. The section 2 of the pen body can, if desired, be constructed of conducting material throughout. The cap 51 is preferably set up of non-conducting material. 120 125 130

It is thought the many advantages of a fountain pen as set forth can be readily understood, and although the preferred embodiment of the invention is as illustrated and described, yet changes in the details of construction can be had which will fall within the scope of the invention as claimed.

What I claim is:

1. A fountain pen comprising a pen body, a combined lamp socket forming element and reservoir support removably mounted in the forward portion and extending lengthwise of the bottom of said body, a lamp arranged forwardly of and having its plug extending through said element, a contact member carried by and insulated from said element and contacting with the rear end of the lamp plug, a contact arranged within said body rearwardly of said element and spaced from said member, and a battery arranged in the rear portion of said body and gravity shiftable towards the lamp to have its terminals simultaneously engage said member and contact to close the lamp circuit when the pen is positioned for writing.
2. A fountain pen comprising a pen body, a combined lamp socket forming element and reservoir support removably mounted in the forward portion and extending lengthwise of the bottom of said body, a lamp arranged forwardly of and having its plug extending through said element, a contact member carried by and insulated from said element and contacting with the rear end of the lamp plug, a contact arranged within said body rearwardly of said element and spaced from said member, and a gravity shiftable battery arranged in the rear portion of said body, said battery having one of its terminals permanently contacting with said member and its other terminal normally spaced from said contact, said other terminal engaging with said contact to close the lamp circuit when the pen is positioned for writing to provide for the gravity shifting of the battery towards the lamp.
3. A fountain pen comprising a pen body, a combined lamp socket forming element and reservoir support removably mounted in the forward portion and extending lengthwise of the bottom of said body, a lamp arranged forwardly of and having its plug extending through said element, a contact member carried by and insulated from said element and contacting with the rear end of the lamp plug, a contact arranged within said body rearwardly of said element and spaced from said member, a battery arranged in the rear portion of said body and gravity shiftable towards the lamp to have its terminals simultaneously engage said member and contact to close the lamp circuit when the pen is positioned for writing.
4. A fountain pen comprising a pen body, a combined lamp socket forming element and reservoir support removably mounted in the forward portion and extending lengthwise of the bottom of said body, a lamp arranged forwardly of and having its plug extending through said element, a contact member carried by and insulated from said element and contacting with the rear end of the lamp plug, a contact arranged within said body rearwardly of said element and spaced from said member, and a battery arranged in the rear portion of said body and gravity shiftable towards the lamp to have its terminals simultaneously engage said member and contact to close the lamp circuit when the pen is positioned for writing.
5. A fountain pen comprising a pen body, a removable inner shell mounted therein and threadably engaging therewith, said shell having its bottom formed with an opening and further formed with a pair of inwardly extending lengthwise disposed opposed flanges positioned above the bottom of the pen body when said shell is mounted therein, and a lamp socket holder seated on the bottom of the pen body, extending through said opening into the shell and having its lower portion overlapped by said flanges whereby the holder is detachably secured in position.
6. A fountain pen comprising a pen body, a removable inner shell mounted therein and threadably engaging therewith, said shell having its bottom formed with an opening and further formed with a pair of inwardly extending lengthwise disposed opposed flanges positioned above the bottom of the pen body when said shell is mounted therein, and a lamp socket holder seated on the bottom of the pen body, extending through said opening into the shell and having its lower portion overlapped by said flanges whereby the holder is detachably secured in position, said holder provided with means for supporting the lamp socket at an upward inclination and further having means for supporting a contact member associated with the lamp socket.

In testimony whereof, I affix my signature hereto.

JOHN J. DEVINE.
